JEAN EMILE PÉRISSET, SURNAMED EMMANUEL PÉRISSET, OF CHATILLON-SOUS-DAGNEUX, FRANCE.

MAGNETO.

Application filed July 11, 1925, Serial No. 43,023, and in France May 19, 1925.

The present invention is adapted to remedy a number of inconveniences in existing high tension magnetos and particularly the difficulties presented by the adjustment of the breaking device.

The magneto in accordance with the invention is essentially characterized by its breaking device, comprising two platinized nonadjustable contacts and a cam capable of determining the separation of these two contacts and adjustable from the exterior during the operation by means of a member which can be operated and easily locked.

This magneto presents various other characteristic arrangements which will be described in detail and claimed hereinafter.

In the accompanying drawing,

Fig. 1 is a longitudinal section.

Fig. 2 is a half plan view and half sectional plan view.

Fig. 3 is a half section and a half rear view.

Fig. 4 is a half section and a half front view.

Fig. 5 represents the interior of the front plate of the magneto.

Fig. 6 shows the inner face of the rear plate.

Fig. 7 is a face view of the spring 4 in Fig. 1 and Fig. 8 a sectional view on line 8—8 of Fig. 7 of the adjusting and stop spring.

The magneto comprises a frame *a* forming a housing or case and closed at its front part by a removable cheek *a*¹ secured by means of screws *a*². A horseshoe magnet *b* is horizontally arranged and fitted in such a manner that its two branches embrace the frame by sliding along its side faces.

This magnet is held by means of a single needle screw *c* screwed in the frame and fitting in a small notch provided in the head of the magnet. Two terminals *d* (only one being shown) made of insulating material serve as means for the attachment of the high tension current wires and carry contact pieces *d*¹ which are arranged within a large cavity *e* provided between the frame and the head of the magnet. These contact pieces are each constituted by a vertical rod terminating in a point *d*² which forms with the edge of an orifice *e*¹ provided in the frame opposite the point *d*² a safety gap. At the point where these

contact pieces receive the high tension current from the secondary winding, they are each provided with a reduced portion *6* presenting a concave surface which gives them a spark striking surface instead of a spark striking point.

The advantages of the above arrangement causes a distribution of the spark gap over a larger surface instead of concentrating the spark at a single point in case of variable advancement and thus preventing injury to the elements to and from which the spark makes its jump.

The top of the terminals *d* is provided with a knob having a pointed screw *7* which can secure the conducting cable by penetration or any other manner. These terminals are moreover provided with a securing means through the medium of a spring *8* in the shape of a hair-pin, which fits in a groove provided for that purpose and of a rubber or like washer *9* forming a tight joint.

The cavity *e* perfectly aerated by the orifices *e*¹ serves therefore as striking chamber for the breaking sparks and eventually as a chamber in which the sparks are produced either during normal operation of the device or when a spark is had between the point *d*² and the cavity *e*¹.

The rotor has a drum *f* which supports the core *f*¹ on which are arranged the primary and secondary windings.

A cylindrical condenser *g* is held by two small plates *10* rigid with the front part of the rear casing and which press on one of the poles of the condenser *g* with interposition of an insulating material.

The insulated pole *14* of the condenser *g* is connected with the primary winding through the medium of a wire *20*, which passes through the armature in a groove *21* formed lengthwise of the latter, and of the ring *K* to which it is secured by means of one of the thimbles *13* which serve to secure this ring.

In the recess of the condenser enters the front part of a high tension current distributor *h*, the rear flared part of which projects into the chamber *e*. This distributor is constituted by an insulating body perforated at its center for following the passage of the high tension current feeding wire. This wire leads to a distributing finger *h*¹

arranged in an eccentric position on the rear flared portion of the distributor. When the rotor rotates, this finger comes alternately opposite the concave surface 6 of each of the 5 contact pieces d^1 and distributes the high tension current to the sparking plugs connected to each of these contact pieces. The distributor h is held in position, in the axial direction on the end of the drum, on the 10 one hand, by means of its rear flared portion and, on the other hand, by a ring 11 arranged between the ball-bearing 12 and the flared portion of the distributor.

A corresponding groove is provided on the 15 rear face of the plate of the rotor and on the distributor for receiving the ring 11. The breaking device of the primary winding, is arranged at the front part of the magneto.

It comprises a spring i secured on the 20 rotor at right angles to the axis and recessed at its center for allowing the passage of this axis. This spring which is electrically connected to the body, carries an abutment or shoe i^1 , made of insulating material, and a 25 platinized contact i^2 secured on the same in an invariable position.

The two contacts are arranged opposite each other and the spring i constantly tends to press the contact i^2 upon the contact k^1 , so 30 as to ensure the connection between the primary winding and the body through the medium of the ring K .

This ring forms moreover a commutator for the primary winding; in fact, a brush L 35 (Fig. 1) is constantly pressed upon the outer surface of the ring. This brush is arranged on a contact piece L^1 which can be placed in body connection through the medium of a wire, so as to permit to interrupt at will the 40 ignition.

This contact piece is secured on the inspection cover m of the primary winding; this cover is constituted by an insulating block which can be freely removed and can be 45 immobilized by two push-pieces 5. The said cover closes an opening m^1 provided at the upper part of the frame.

The breaking of the primary winding is obtained by the separation of the contacts 50 i^2 and K^1 by means of a cam n on which bears, upon rotation of the rotor the abutment i^1 of the spring i . The spring then yields and separates the contact i^2 from contact K^1 . The cam is carried by a circular 55 bracing member n^1 . The cam and the bracing member are ring-shaped so as to allow the passage of the axis of the rotor. The bracing member is pushed back against the inner face of the cheek a^1 by a spring n^2 in 60 the shape of a cup and taking a bearing against a ledge.

The adjustment of the distance separating the platinized contacts upon breaking, is effected by axial displacement of the cam n .

65 For that purpose, a number of orifices paral-

lel to the axis of the rotor are formed in the cheek a^1 . These orifices allow the passage of push pieces P^1 carried by a ring 1 (Fig. 1) integral with the said push pieces; this ring is arranged within the adjusting crown P which is recessed for receiving the ring 1. By screwing this crown, the ring 1 and the push pieces are pushed.

In the adjusting crown P are formed notches 3 (Fig. 2) in which can fit the tongue shaped end 4^a of an adjusting and stop spring 4 (Fig. 1); this arrangement allows to easily effect the adjustment. The said spring 4 is in the shape of a crescent (Fig. 7) and can be secured on the front cheek of the machine; when the tongue 4^a is fitted in one of the notches of the crown P , it prevents any unloosening of the latter; for causing the crown P to rotate, the spring is released. This locking system has the advantage of preventing an untimely unloosening and determining misadjustment. The adjusting crown P is screwed on a central projection of the cheek a^1 ; by screwing it on more or less, the brace and the cam are axially moved, the springs n^2 holding this brace and cam pressed against the push pieces. From the position of the cam thus obtained depends the spacing apart of the two platinized contacts.

Claims:—

1. In a high tension magneto, comprising an outer adjusting system provided with a cam, a particular arrangement of this adjusting system consisting of a hollow crown, 100 a ring within this crown, push pieces on this ring, these push pieces being permanently secured in position and acting on the adjusting cam.

2. In a high tension magneto, a breaking 105 device comprising an adjusting means for the breaking device, a locking device for the breaking device including an adjusting crown having notches, and a crescent shaped spring carrying a tongue which fits by itself in the said notches, both the adjusting means and locking device being actuated from the exterior.

3. In a high tension magneto, a housing, 115 circuit breaking members in the housing, an insulating cover for the housing and independent of the circuit breaking members, movable push pieces for holding the cover in position which allow its removal under the action of a vertical traction, the cover giving free and wide access to the circuit breaking members, a spring brush supported by the cover, and a rotary member with which the brush engages, the rotary member being connected to the primary 120 member and to a contact piece which can be earthed for interrupting the ignition at will.

4. In a high tension magneto, a housing, a drum in the housing, a condenser in the drum, and two small plates rigid with the 130

drum and bearing on the condenser with interposition of an insulating material.

5. In a high tension magneto, a condenser, a primary ring, thimbles for securing the ring, an armature having a longitudinal groove and an insulated cable secured to the condenser and to one of the securing thim-

bles, said cable being arranged in the groove of the armature.

The foregoing specification of my "magneto" signed by me this 26th day of June, 1925.

JEAN EMILE PÉRISSET,
Surnamed Emmanuel Périsset.
